UNITED STATES PATENT OFFICE

2,602,567

DISPENSING CONTAINER

Robert Carl Geon, Toledo, Ohio

Application November 21, 1949, Serial No. 128,652

1 Claim. (Cl. 220—93)

1

This invention relates to dispensing of congealed materials, especially ices and ice cream, and has to do with rendering more conveniently available bulk quantity from which service portions are to be taken.

This invention has utility when incorporated with single service bulk containers, as of the paper can, drum or canister type, as located in a freezer or cold storage cabinet, such as in association with a soda fountain. Opening of the insulated-wall cabinet exposes the open top of a tubular bulk container, say for five gallon portion of ice cream. With such vessel or container in the range of say 9" in diameter and approximately twice that depth, the fountain attendant gripping a service portion gathering tool and reaching into the container thru the open top of the cabinet has full length of forearm entering the cabinet opening with the container contents hardly half removed.

Under the practice adopted for achieving the advantages of this invention, an intermediate or medial diaphragm or partition is located in the container. When this is accorded attention at the place of dispensing, the initially worked-in end as up, may have its side walls to some extent cleared of ice cream fragments. Thrusting of the diaphragm fully crosswise may cause its rim to act as a supplemental scraper for locating the undispensed bulk of the ice cream below the insert diaphragm. Upon establishing this minor volume for the container as a chamber more or less completely filled with the undispensed ice cream, such can is lifted from the cabinet. As out of the lid opening, the can is oriented, to locate what was the top, now downward. In the event there be a slip-on closure for each end of the container, that one which was at the bottom is now up and may be placed on the other end of the container, as dropped back into the cabinet, void container section down. The open upper end of the apparently full minor container section is now in proximity to the cabinet lid for dispensing regular service down to the diaphragm.

In carrying out the invention as herein disclosed, the diaphragm is provided with an anchoring control. With the paper side wall drum for the container, an item for discard as the ice cream is taken therefrom, it is in order for the fountain attendant, first to remove the diaphragm and its control from the now-open ended tube, as the slip-on end closures are off. The diaphragm and its control are retained for reuse. The normal sanitation processes as current at the

2

soda fountain for the service portion dispensers is desirably adopted for the diaphragm.

Referring to the drawings:

Fig. 1 is a front view from the behind-the-counter side of a soda fountain with an associated cooling or chill cabinet, portions being broken away to show bulk containers therein;

Fig. 2 is a side elevation, with parts broken away of a paper drum or bulk ice cream container, with the ice cream about half taken therefrom;

Fig. 3 is a medially-in-section view terminally in elevation of the drum of Fig. 2 in which there is introduced a diaphragm or minor-capacity establishing partition for isolating the upper emptied section or chamber from the lower charged section;

Fig. 4 is a similar view of the same container, but oriented from the position shown in Fig. 3, and from which upper minor-chamber-section service portions of the ice cream have been removed;

Fig. 5 is a fragmentary plan view on an enlarged scale of the insertable diaphragm of Figs. 3, 4, from the control side thereof, showing in dotted lines the penetration point as withdrawable in reverse direction of turning; and

Fig. 6 is a side elevation of a portion of the operating knob, with the mounting details thereof shown in section.

A soda fountain unit is shown with spigots for discharge into cups or glasses as placed by the attendant on a ledge 2. Looking from the behind-the-counter side toward the cabinet, there is downward from the ledge 2 an inclined top 3, with removable closures or lids 4 to expose top openings 5 of bulk containers 6 in a cold storage or chill chamber 7 of the cabinet. An attendant grasping a service portion gathering tool 8 has full length of forearm 9 extending downward from the cabinet top portion 3 in a depth reach hardly to half the contents of the container 6. This down-reach for the operator or attendant is awkward, especially if there be requirement for further down operation. In the retail course of dispensing of ice cream and ices, it is important that the bulk reserve be in a chill chamber. To the extent that the service portion to be dispensed be in proximity to the opening 3, there is possible more rapid and convenient service to patrons.

The container drum or tube 6 may be a fiber or paper stock spiral wrap, say water proof and with appropriate lining suitable for congealed edible products, as ice cream and ices such as 55 of fruit or other flavors. This open ended tube

6 may have endless channel crimped anchor end trims 10. As a single chamber bulk unit, each end may be provided with a closure disk 11 having an outer rim or flange 12, to effect snug slip-on connection with the tube 6. Upon placing of a bulk fully charged container 6 with commodity 13 therein to be dispensed, such is fully up to the under side of the top end closure 11, 12, as removed. This locates the commodity 13 in readily accessible distance when a lid 4 is thrown back. That is, the open end 5 of the fully charged container 6 is in proximity to the top 3 of the cabinet.

The normal dispensing operation by removing service portions, takes away from the commodity 13 to leave a somewhat irregular region 14 with a void or empty region 15 upward therefrom (Fig. 2).

As the depth for dipping out service portions becomes inconvenient to the attendant, there may or may not be clearing of the side walls of the region 15. This may be for dispensing in service portions, or a sort of leveling off. In view of the fact that ice cream and ices in the congealing operation may have bulk increase of nearly double that for the liquid, it is important for the soda fountain operator that application of pressure or crowding the bulk residue be kept to a minimum, for the service portions are usually volume measured, and as retaining the stage at congealing, normally are considered to have maximum of flavor or taste value in such unpacked state. While bearing this point or merchandising practice in mind, the attendant may insert the diaphragm.

A disk 16 has centrally of one side and welded to respond as integrally therewith a short stem 17 with a groove 18 inward from its free end. Peripherally of the disk 16 and from its opposite side is a slightly flaring flange 19. The disk 16 may be of light weight and thin sheet metal with reinforcement value arising from the flange 19 integral therewith. The preferred practice is to insert the disk 16 in the opening 5 in a plane approximately at right angles to the axis of the drum or tube 6. In this operation, the flange 19 coacts in a close scraping relation to clear the inner wall of the region 15 of the tube 6 in moving such portion of the commodity 13 to approach a level state with the flange carrying face of the disk 16. Should the experience in practice be that the fit between the disk periphery and the inner face of the drum wall 6 be so close that resistance is met in causing the disk so to descend due to non-escape of air from this piston operation, vent means may be adopted by a port or ports 20. These ports 20, preferably are sufficient to allow the air to escape but so minor in dimension as not to tend to cause the ice cream or commodity 13 to ooze therethru.

A knob, grip or handle 21 has an axial recess 22 to fit over the stud or stem 17. A set screw 23 connects the grip 21 for rotation relatively to the disk 16 thru engaging the groove 18. In this assembly, the grip 21 is held axially of the disk 16 with rotation on the stem 17 permitted to a limited degree.

Fixed with the disk 21 is a minor disk or actuator plate 24. The plate 24 is an operative means to lock or anchor the diaphragm 16, effected as herein disclosed by an expansion device, with the drum 6. The device may comprise a plurality of elements, herein shown as three, with uniform angular distribution in 120° spacing. Openings 25 are similarly uniformly spaced in

the plate 24. Rivet ends 26 retain angle offsets 27 as upward thru the openings 25. The offsets 27 are bearings for radially extending thrust arms 28.

- 5 Near the outer edge of the disk 16 on the side thereof away from the flange 19, guide lugs 29 provide slide ways for the respective arms 28 inward from taper points 30 of the arms. From an outward thrust position (Fig. 5), the grip 21 10 may be given an angular twist or turn of say near 90° to a retracted position 31 from this counter-clockwise shifting. The recover, or reverse clockwise turning of the grip 21 may be to an extent of say 5° or 10° beyond radially aligning the direct radial direction for the arm 28 to bring a 15 struck-up lug or stop 32 from the crank disk 24 against the arm 28. This is a limit throw by turning in the direction of the arrow 33, and in practice is a minimal of retraction for the point 20 30. Accordingly any loosening at rupture regions 34 does not free the arm from frictional engagement there, while the beyond-radial location is a sort of toggle lock against in-thrust from the point 30.
- 25 During the insertion of the diaphragm or partition 16 into a container 6, the knob 21 is at its counter-clockwise retracted limit as a positive held position with the points 30 radially inward from the disk 16 outer edge. Upon the diaphragm insertion or thrusting to the region of the material 13, and with the disk 16 held at right angle to the axis of the drum, a clockwise turn of the grip 21 completes setting for the diaphragm, as the stop 32 limit is reached.
- 35 This placing of the disk 16 as a diaphragm may be effected with the container 6 still in the cabinet chamber 7. There is thus provided, now at the lower portion or half, a charged container chamber 35, and thereabove an empty or void chamber 36. The attendant may now remove the two-chamber or compartment container from the cabinet chamber 7, orient the container and replace in the cabinet chamber 7. In the event there be slip-on closure 11, 12, at end opening 37 40 remote from the opening 5, the removal of this closure may be effected before lowering the two-compartment container back into the chamber 7. This removed cap or closure 11, 12, instead of a cut-out, may be slipped over the opening 5 to provide a bottom for the replaced container to 45 be reset in the chamber 7. Should there be any seepage or sifting of commodity past the insert partition 16, this closure 11, 12, may serve as a sort of cup or retainer to promote retention of 50 desirable clean and sanitary conditions in the retailing operations. The now top opening 37 is in 55 convenient location at the top 3 of the soda fountain dispensing cabinet for service portions to be taken of the commodity 13 from the chamber 35. It follows that for this residual commodity 13 there is now retained ready access advantage in the dispensing from the chamber 35 as from the upper section of the original bulk chamber 6 in its full charge. The operation as 60 disclosed relates to the sliding into the partially emptied bulk container of means providing an intermediate partition, as of possible advantage over congealing or otherwise establishing a plural chamber container for dispensing therefrom.
- 65 For chill-avoiding comfort in handling, the knob 21 may be of heat insulation composition or wood. The other portions of this re-useable diaphragm may be of metal, appropriately coated to conform to sanitary service. In this connection an oiled paper wafer or similar facing may be on 70 75

the flange side of the disk 16 and replaced from each use.

While as hereinbefore stated that the selectable placement partition may be of metal, acceptable service is available from such unit even of plastic.

Due to the fact that the operator or attendant has in hand the grip 21 with a thrusting thereof down into the partially emptied container 6, any view of the disk arms is obstructed by the attendant's forearm extending into the opening 5. As disclosed, the points 30 are retracted before lowering the disk 16. Upon reaching the descent limit, as for the commodity 13 to be against what is then the lower or flange-carrying face of the disk 16, the operator may give a clockwise turn to the grip 21. Notwithstanding inability to see just how far this is done as to whether there is full thrust or the points 30 protrude, there is the "feel" response as the stop 32 precludes further grip clockwise turning. It is now up to the operator to remove the container, which now has the residual commodity sealed off from top access, from the cabinet. Preferably this may be by gripping the rim 10, or even by an up-pull on the grip 21. However this latter course depends upon how tough the container side walls may be to withstand this operation. During this lifting and orienting of the container, the toggle lock scheme prevents any thrust upon the projecting points 30 to push such back to release the partition. Accordingly there is positively avoided the hazard of re-locking the oriented container in the cabinet, to have the insert partition give way for the residual contents to follow its descent, thereby depriving the attendant of any advantage, for then it requires the full depth lifting out of the service portions from the container. The toggle lock scheme for resisting exterior of the container in-thrust upon the points 30, establishes a stable operating condition for the vendor of ice cream, or other service portions from bulk type of containers as herein disclosed.

What is claimed and it is desired to secure by Letters Patent is:

A tubular container open at opposite ends and

having pierceable side walls and a uniform cross section throughout its length, separate removable closures for said ends, and an insertable partition corresponding in shape and size to the internal cross section of said container and slideable axially in said container to scrape the inner wall of said container, anchoring means on said partition comprising a plurality of radially movable outwardly extending piercing elements mounted on said partition, and a centrally arranged manually actuatable means connecting the inner ends of said piercing elements for extending and retracting said elements, the elements when extended piercing said walls of said container to anchor said partition in place, whereby said partition may be fastened inwardly from the ends of said container to divide the container into two parts each of which parts may be entered from a different end of said container, so that after the contents of the container are partly removed from one end thereof the partition may be inserted in that end and anchored in place onto the top of remaining contents in the container and the container may be inverted and its other end opened to remove said remaining contents from the other end of said container with the inserted partition now acting as the bottom of the contents now remaining in the container.
